(57) **CLAIM**

The ornamental design for a front pack baby carrier cover, as shown and described.

DESCRIPTION

FIG. 1 is a front, top and right side perspective view of a front pack baby carrier cover embodying my new design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a top plan view thereof, the bottom plan view being a mirror image.

The crisscross pattern of lines in the drawings represents material and is understood to be distributed uniformly over the surface of the front pack baby carrier cover.
